UEL REYNOLDS, OF NEW YORK, N. Y.

Letters Patent No. 65,119, dated May 28, 1867.

IMPROVEMENT IN SHIFTING-RAILS FOR CARRIAGE TOPS.

The Schedule referred to in these Letters Patent and making part of the same.

TO ALL WHOM IT MAY CONCERN:

Be it known that I, UEL REYNOLDS, of the city and State of New York, have invented, made, and applied to use a certain new and useful Improvement in Shifting-Rails for Carriage Tops; and I do hereby declare the following to be a full, clear, and exact description of the said invention, reference being had to the annexed drawing, making part of this specification, wherein—

Figure 1 is a plan of the said shifting-rail upon a carriage seat, and

Figure 2 is a section of the same at one side of the seat.

Similar marks of reference denote the same parts.

Heretofore the shifting-rail that connects the carriage top with the seat has been made of iron forged to shape with the slat-iron and prop-block forged or welded upon it. This construction is costly, and with these shifting-rails the prop-blocks and slat-irons cannot be constructed separately, but have to be made with the necessary shoulders and screw-threads after they are welded or formed upon the shifting-rail. Besides this, the trimming or covering of the shifting-rail has had to be sewed on, as nails or tacks could not be employed.

The nature of my said invention consists in a wooden shifting-rail, bent to the proper shape for extending around the ends and back of the seat, and connected removably thereto by bolts and nuts, and fitted with iron prop-blocks and slat-irons securely attached by screws to said shifting-rail, and receiving the slats and props of the carriage top. This wooden shifting-rail is much cheaper than the iron ones, is equally durable, the iron screws and attachments can be finished up with facility separately from the shifting-rail, and the covering or trimming of the said shifting-rail can be attached by nails and tacks in a much more acceptable style than by sewing.

In the drawings *a* is the bottom, *b* the back, and *c e* the ends of the carriage seat. *d d* are the iron straps running up said sides and ends, and terminating with eyes, as usual: *h* is my wooden shifting-rail, bent to shape, and provided with the bolts *e e*, entering the eyes at the ends of the straps *d*, and removable therefrom with the carriage top or firmly connected thereto by bolts. *g* is the back of the seat above the shifting-rail *h*, and *ff* are the prop-blocks and *kk* are the slat-irons. These are each formed with the projecting screw-pins extending from the metal strap or plate that is let into the shifting-rail, and permanently secured thereto by means of screws. Metal rings or bands, *t*, may be employed, as shown, to aid in connecting the straps to the rail and preventing the wood splitting.

What I claim, and desire to secure by Letters Patent, is—

The wooden shifting-rail to which the metal slat-irons and prop-blocks are attached, as set forth.

In witness whereof I have hereunto set my signature this twenty-first day of March, A. D. 1867.

UEL REYNOLDS.
